CLAIM

The ornamental design for a paint vessel cover, as shown and described.

DESCRIPTION

FIG. 1 is a top perspective view of a paint vessel cover showing my new design;

FIG. 2 is a reduced scale top plan view of the paint vessel cover showing my new design;

FIG. 3 is a bottom plan view of the paint vessel cover showing my new design;

FIG. 4 is a front elevation view thereof;

FIG. 5 is a rear elevation view thereof;

FIG. 6 is a right side elevation view thereof; and,

FIG. 7 is a left side elevation view thereof.

The broken lines in the drawings are included for the purpose of illustrating environmental structure and form no part of the claimed design.
